(57) **CLAIM**

The ornamental design for a plug for medical connectors and drug infusion ports, as shown and described.

DESCRIPTION

FIG. 1 is a perspective view of a first embodiment of a plug for medical connectors and drug infusion ports showing my new design from the front end and one side, the opposite side being a mirror image of that shown;

FIG. 2 is a perspective view thereof, shown from the back end and side;

FIG. 3 is a perspective view of a second embodiment of a plug for medical connectors and drug infusion ports showing my new design from the front end and one side, the opposite side being a mirror image of that shown; and,

FIG. 4 is perspective view thereof, shown from the back end and side.
